UNITED STATES PATENT OFFICE.

ANDREW BICE TRAVIS, OF BRANDON, MICHIGAN.

IMPROVEMENT IN SEED-DRILLS AND CULTIVATORS.

Specification forming part of Letters Patent No. 34,918, dated April 8, 1862.

To all whom it may concern:

Be it known that I, A. B. TRAVIS, of Brandon, in the county of Oakland and State of Michigan, have invented a new and Improved Cultivator and Seed-Drill; and I do hereby declare that the following is a full, clear, and exact description of the same, reference being had to the accompanying drawings, making a part of this specification, in which—

Figure 1 is a side sectional view of my invention, taken in the line *x x*, Fig. 2; Fig. 2, a plan or top view of the same; Figs. 3 and 4, detached views of a tooth pertaining to the same.

Similar letters of reference indicate corresponding parts in the several figures.

The object of this invention is to obtain a cultivator and seed-drill the teeth of which may be readily shifted laterally by the attendant in order to conform to any irregularities in the rows of a crop under cultivation, and also to evade obstructions—such as stones, stumps, &c.—which may lie in the path of the teeth.

The invention has further for its object a simple means for regulating the depth of the penetration of the teeth in the soil.

To enable those skilled in the art to fully understand and construct my invention, I will proceed to describe it.

A A' represent two wheels, which are placed loosely on an axle, B, having a draft-pole, C, attached to its center. On the axle B there is placed longitudinally a bolster, D, which is retained in proper position by the guide-pins *a a*, said pins projecting down from the bolster, one near each end, and passing loosely through holes in the axle E E are two thumb-screws which pass up through the axle B, one near each end, and bear against the under side of the bolster. (See Fig. 1.)

F is a V-shaped frame, which is formed of two oblique bars, *b b*, connected together at their front ends, and having their back diverging ends framed into a cross-bar, *c*, which is fully equal in length to the axle B. A cross-bar, *d*, is also attached to the oblique bars *b b* some distance in front of the bar *c*, parallel with it, but not so long. (See Fig. 2.) The oblique bars *b b* of the frame F rest on the bolster D, and the front ends of said bars are connected by a hinge or joint, *e*, to the draft-pole C.

To the cross-bar *c* there are attached a series of inclined standards, *f*, each having a tooth, *g*, attached to its lower end. The teeth *g* may be of cast or wrought metal, each being provided with a socket, *h*, at its upper end to receive the lower ends of the standards *f*, which are of wood. The teeth *g* may be of any suitable form, and different kinds may be used to suit the character of the work to be performed. The form of the teeth used in this particular instance will be fully understood by referring to Figs. 3 and 4. The two standards *f f* of the bar *c*, which are at each side of the center standard, *f*, have their upper ends fitted in oblong mortises *i* in the bar *c*, and said standards are secured in their mortises *i* by keys or wedges *j*. (See Fig. 2.) These wedges *j* may be driven into the mortises *i* at either side of the standards *f*, and this consequently admits of a certain degree of lateral shifting of said standards. All or any number of the standards *f* may be thus attached to the bar *c*. This adjustment of the standard *f* enables the attendant to place the teeth so that they may work nearer to or farther from the rows of plants under cultivation. The standards *f* do not all have the same degree of inclination, one set, which are secured alternately with the other in the bar *c*, being more inclined than the intermediate ones. All the standards are braced by rods *k* from the cross-bar *d*.

To the under side of the draft-pole C, near its back end, there is attached a metal bar, G, which extends a trifle back of the axle B, and has a slot, *l*, made in it to receive the lower end of a lever H, the upper end of which is attached to a rock-shaft, I, placed longitudinally in the frame F, and having handles J attached to it.

When the implement or device is used as a seed-drill, any suitable seed-distributing device is placed on the frame F.

From the above description it will be seen that as the implement is drawn along, the attendant may shift the frame F, and consequently the teeth *g*, either to the right or left by operating the rock-shaft I, through the medium of the handles J J, and it will also be seen that the depth of the penetration of the teeth *g* into the earth may be regulated as desired by adjusting the thumb-screws E E, thereby raising or lowering the back part of the frame F. The hinge or joint *e* of the frame F

is so constructed as to admit of the vertical as well as the lateral adjustment of said frame.

If desired, the back part of the frame F may have adjustable bars attached with rollers at their lower ends, to serve as a support for the back part of said frame. These bars and rollers are shown in blue outline in Figs. 1 and 2, and teeth provided with turn-shares may also be used when necessary, and also tubular teeth, as shown in blue. As before stated, however, any form of teeth may be used.

Having thus described my invention, what I claim as new, and desire to secure by Letters Patent, is—

The frame F, having the standards f and teeth g attached, connected to the draft-pole C by the universal hinge or joint e resting on the adjustable bolster D, and operated through the medium of the rock-shaft I, lever H, and slotted bar G, all arranged as and for the purpose set forth.

ANDREW BICE TRAVIS.
